UNITED STATES PATENT OFFICE.

MELVILLE A. CLARK, OF SYRACUSE, NEW YORK.

HARP.

1,351,468.

Specification of Letters Patent. Patented Aug. 31, 1920.

Application filed September 9, 1916. Serial No. 119,194.

To all whom it may concern:

Be it known that I, MELVILLE A. CLARK, a citizen of the United States of America, and resident of Syracuse, in the county of 5 Onondaga, in the State of New York, have invented new and useful Improvements in Harps, of which the following, taken in connection with the accompanying drawings, is a full, clear, and exact description.

10 This invention relates to certain improvements in harps, and more particularly to the means for fretting the strings of that type of harp which is commonly known as the "Clark Irish Harp," similar to that shown 15 in my Patent No. 1,005,157, October 10, 1911, in that it makes use of a system of movable frets for changing the pitch of the various strings.

The main object is to provide means exterior to the frame for connecting and operating the frets in sets or octaves so that those of each set may be operated simultaneously independently of those of the other sets.

I am aware that in the larger standard 25 forms of harps, it is customary to provide means concealed within the neck and hollow body of the frame for connecting and operating the various sets of frets through the medium of pedal levers located at the 30 base of the main body, but in the smaller harps of the type referred to, the use of such pedal-operated means is precluded by reason of the fact that the harp is supported a considerable distance above the floor or 35 natural position of the feet when playing, and I have, therefore, sought to provide simple and comparatively inexpensive means for accomplishing similar results by hand through the medium of external link means 40 and suitable manuals within convenient reaching distance of the operator.

Another object is to enable the different sets of frets to be operated by either hand from either side or face of the harp, and 45 also from an intermediate position between the neck and base.

Other objects and uses relating to specific parts of the fret-operating means will be brought out in the following description.

50 In the drawings—

Figure 1 is a side elevation of a harp embodying the various features of my invention.

Fig. 2 is an enlarged top plan of the same 55 harp showing a portion of the neck in section.

Fig. 3 is an enlarged face view of a portion of the neck of the frame and adjacent portions of two of the links and operating means therefor, some of the frets being 60 shown in section.

Fig. 4 is an enlarged transverse vertical sectional view taken on line 4—4, Fig. 3.

Fig. 5 is an enlarged vertical sectional view taken on line 5—5, Fig. 1. 65

Fig. 6 is an enlarged face view of one of the rocking sectors on the front post of the frame showing the manner of attaching one of the links thereto for operating the corresponding link for one set of fret keys. 70

Fig. 7 is an enlarged horizontal sectional view of one of the frets and adjacent portion of the neck in which it is mounted, showing its connection with one of the links leading to the corresponding finger piece on 75 the post and also showing its connection with the links leading to other frets on the neck.

The frame of the harp comprises the usual hollow body or column —1—, the 80 front post —2— and the neck —3— rigidly connected to each other in any well-known manner for supporting the strings —4—, the lower ends of which are attached to the sounding board of the hollow column —1—, 85 while their upper ends are connected to the usual tuning pins —5—.

Suitable frets —6— (one for each string) are systematically mounted upon the upper portion or neck —3— of the frame and are 90 preferably journaled in suitable bearings —7— adjacent their respective strings so as to rock about parallel horizontal axes, each fret being provided with an eccentrically disposed contact roller —8— movable into 95 and out of engagement with its corresponding string for varying its pitch as the fret is rocked in reverse directions, each fret being returned to and held in its normal position by a retracting spring —9—, as 100 shown more clearly in Figs. 3 and 4.

The frets of each set corresponding to the strings of the same denomination throughout the range of the harp are connected for simultaneous movement by links 105 —10— which may be shifted in reverse directions by a finger-piece or manual —11— so that the operation of any one of the manuals from its normal position will fret all of the strings of like denominations 110 simultaneously.

It is, therefore, evident that in order to

fret all of the strings of one denomination throughout the entire range of the harp, it is necessary to provide only one finger piece or manual for each set of frets, or seven manuals in all,—that is, one manual for all of the C strings; another for all of the D strings; a separate manual for all of the E strings, and so on throughout the octaves.

- 10 For convenience of operation, the several frets are provided at one end, preferably at the same side of the neck at which the strings are located, or left-hand side of the harp, with downwardly projecting crank 15 arms —12— to the lower ends of which the links —10— of each set are pivotally connected in such manner as not to interfere with the free operation of any one of the manuals independently of the others.
- 20 The right-hand end of one of the frets of each set protrudes beyond the adjacent or right-hand side of the neck —3— of the frame and is provided with a crank arm 25 —13—, constituting an operating lever or finger-piece by which the corresponding set of frets may be adjusted by the right hand to their operative positions.

Each fret is normally held in such position that its contact member —8— is substantially midway between and out of contact with the adjacent strings —4—, but is movable through an arc of approximately ninety degrees to a position in a direct line between its point of contact with the string 35 and its axis of movement so that the pressure of the string against the contact member —8— will be toward said axis and will automatically hold the fret in its fretting position, but when moved slightly 40 from such position will be automatically returned to its normal position by its retracting spring —9— aided by the tension of the string engaged thereby, the roller contact —8— serving to reduce friction and 45 consequent wear of the strings.

In some instances, it may be found more advantageous to provide means for operating the several sets of frets at points some distance below the neck or within easy 50 reaching distance of the left hand which operates more often upon the longer strings near the front post, and for this purpose I have provided the first seven frets from the front, with additional crank arms —14—. 55 The arms —14— are connected by wires —15— with separate finger pieces or manuals —16— which are journaled in the front post —2— at points some distance below the plane of intersection of the front string 60 with said post so as not to interfere with the free operation of the strings by hand, the several manuals —16— being disposed in planes one above the other to permit them to be operated freely without interference 65 one with the other.

Each of these operating members —16— comprises a rock shaft —17— journaled in a suitable bearing —18— in the post —2— parallel with the axes of the frets and having their outer ends protruding beyond the 70 left-hand side of said post and provided with operating levers or finger-pieces —19— having crank-arms —20— secured thereto and attached to the lower ends of the links 15, Figs. 5 and 6.

As shown more clearly in Fig. 5, the bearing —18— for the rock shaft —17— is 75 slideable in an opening —21— in the post —2— against the action of retracting spring —22—, and is provided on its outer end with cam faces —23— riding against similar cam faces on the adjacent side of the crank arm —20— so that when the finger lever —19— and crank arm —20— are shifted from their normal positions to fret the corresponding set of strings, the cams on the inner face of the crank arms —20— will ride up the inclines of the cam faces —23—, thereby forcing the bearing —18— inwardly against the action of the spring —22— until the high points of the cams engage each other to hold the lever —19— in its adjusted position.

In order to return the frets to their normal positions, it is simply necessary to start 95 the lever —19— upon its return by a slight touch of the finger, whereupon the cams on the outer end face of the bearing —18— under the pressure of the spring —22— will effect the full return of the lever —19— and corresponding frets which may be operated thereby to their normal positions.

It is, therefore, obvious that when the automatic returning means for the lever —19— is used, the springs —9— may be 105 dispensed with because the link —15— will effect the return of all of the frets of the corresponding set.

What I claim is:

1. A harp having all of its strings attached to the neck at one and the same side thereof, in combination with movable frets, one for each string, mounted on the neck, and operating members for said frets at the 110 opposite side of the neck.

2. A harp having all of its strings attached to the neck at one and the same side thereof, in combination with movable frets, one for each string, mounted on the neck, each fret having operating devices at both 115 sides of the neck.

3. A harp having movable frets for its several strings, connected in octave sets for simultaneous movement of those of each set, each set having a finger piece projecting 120 some distance below the neck for operating the frets of that particular set.

4. A harp having frets for its several strings mounted upon the neck and connected in octave sets, each set having a sepa- 125

rate operating means including a finger piece extending some distance below the neck.

5. A harp having individual frets for the several strings journaled on the neck of the harp and connected in octave sets, the connections for each set being provided with a finger piece projecting below the bottom of the neck for simultaneously operating the 10 frets of that set.

6. In a harp, a set of frets for certain strings, connections between said frets for causing them to move in unison, and means including a finger-piece on the front post of 15 the harp for shifting said connections.

7. In a harp, the combination of a fret, a movable finger-piece on the front post of the harp, connections between said finger-piece and fret for operating the latter, and 20 means for automatically returning the finger-piece to its normal position after being started by hand.

8. A harp having individual frets for its several strings connected in octave sets for simultaneous operation of the frets of each 25 set, the connections for each set being provided with individual finger pieces projecting below the under side of the neck at one and the same side thereof.

9. A harp having individual frets for its 30 several strings connected in octave sets for simultaneous operation of the frets of each set, the connections for each set being provided with individual finger pieces projecting below the under side of the neck at one 35 and the same side thereof, said frets having additional individual finger pieces at the opposite side of the neck.

In witness whereof I have hereunto set my hand this 30th day of August, 1916.

MELVILLE A. CLARK.
